UNITED STATES PATENT OFFICE.

JOHN G. DORWARD, OF SAN FRANCISCO, CALIFORNIA.

DEEP-WELL DOUBLE-ACTING PLUNGER PUMP.

Application filed March 9, 1922. Serial No. 542,344.

To all whom it may concern:

Be it known that I, JOHN G. DORWARD, a citizen of the United States, residing at the city and county of San Francisco and State 5 of California, have invented new and useful Improvements in Deep-Well Double-Acting Plunger Pumps, of which the following is a specification.

This invention relates to pumps, and 10 especially to a deep well double acting plunger pump designed for installation in wells employing casings of limited area.

Deep well pumps are as a rule not only submerged, but in practically every case 15 positioned a considerable distance below the surface of the well, in some instances several hundred feet. In view thereof it can readily be appreciated that accessibility 20 under the best of conditions presents a difficult problem, hence requiring the best of workmanship and material when the working parts, such as valves, plungers, guides, etc., are considered, and further a structure which is simple, substantial and efficient in 25 operation. Practically all deep well pumps fall into the hands of inexperienced help or attendants, who are not mechanics. The pumps are therefore given comparatively little care and they are usually subjected 30 to rough treatment. It is therefore necessary to carefully design the pumps and to arrange all parts so that they cannot be put together wrong or out of their proper place. It is also necessary from a mechanical point 35 of view to properly design all water passages to insure a maximum lift as far as the valves are concerned, and to arrange for proper guides and seats. In the usual double acting deep well pump, it is found that the 40 ports or water passages are small and congested, thereby causing water to race through the ports and pass the valves at high velocity. This has a very erosive effect on all working parts and is the source of nearly 45 all the trouble to which pumps of this character are subjected. Restricted or congested ports and valve passages cause friction, consume power and generally lower the life of the pump and the efficiency. The objects of 50 the present invention are to generally improve and simplify pumps of this character; to reduce the number of parts employed; to insure proper alignment of the reciprocating parts, and proper functioning of the valves; 55 to provide maximum port and valve areas

to reduce the water velocity to a minimum; to provide gravity seated valves throughout, thus eliminating springs, which are liable to breakage, etc., and to provide a structure whereby all working parts may be readily 60 removed for inspection, adjustment or repair, without raising the pump cylinder proper or the discharging casing to which it is attached. Further objects will herein- 65 after appear.

The invention consists of the parts and the construction, combination and arrangement of parts as hereinafter more fully described and claimed, having reference to the accompanying drawings, in which—

Fig. 1 is a side elevation of the pump 70 partially broken away and partially in section.

Fig. 2 is a cross section on line 2—2, 75 Fig. 1.

Referring to the drawings in detail, and particularly to Fig. 1, A indicates the main casing of a well, B the pump cylinder, and C the discharging casing to which the cylinder is attached. The pump proper consists 80 of the cylinder B, a head member D, a plunger or piston 3, a plunger rod 4, a pump rod 5, a coupling 6, a foot valve and seat E, and a pair of check valves 7 and 8. The head of the pump consists of a cylindrical 85 shaped casting, the upper end of which is internally threaded as at 9 to receive the discharge casing C. The lower end is similarly threaded as at 10 and carries the pump cylinder B. Mounted interior of the cylindrical head member D is a pair of valve seat members 11 and 12, and supported thereby are check valves 7 and 8, the function of which will hereinafter be described.

Formed interior of the cylindrical head 95 member, adjacent the upper end, is a tapered seat 13, and supported thereby is the upper valve seat member 11. The lower valve seat member is carried by the upper valve seat member by a threaded connection 100 shown at 14. On the upper end of the lowermost valve seat member 12 is a seat for the valve 7 and formed below the same is an annular packing groove 15, provided for the reception of a sealing ring 16. Similarly formed on the lower end of the member 12 is an annular groove 17, provided for the reception of an inverted packing or sealing ring 18. Formed between the sealing rings 16 and 18 is an annular passage 110

19, and forming communication between said annular passage and the well proper is a plurality of ports 20. Formed exterior of the upper valve seat member 11, below the valve 8, is an annular passage 21, and forming communication between said passage and the upper end of the pump cylinder is a series of exterior passages 22, the function of which will hereinafter be described. The lower end of the member 11 is provided with an integral hexagon nut 11^a to permit breaking of the screw joint 14. Both ends are machined to form a stem and guide for the respective valves 7 and 8. Nut 11^a limits the upward movement of valve 7 and a removable nut 11^b the movement of valve 8. The lower valve seat member 12 is provided with an integral nut 12^a employed for the same purpose as nut 11^a and the extreme lower end is recessed to receive a packing gland nut as shown at 12^b.

The plunger rod employed in the present instance is hollow or tubular in formation as shown in Fig. 1, and as previously stated is connected with the pump rod 5 by means of the coupling member 6. This coupling member serves three functions, first that of a valve seat member; secondly that of a pump rod and plunger rod guide, and third that of a coupling between the plunger rod and pump rod. Mounted within this member and guided thereby is a check valve 23, and forming a guide between the coupling and the discharge casing C is a plurality of arms 24 and guide shoes 25. The coupling member just referred to forms the subject matter of a copending application and is therefore only mentioned briefly.

Secured to the lower end of the plunger 3, or in other words the plunger 4, is a tail rod cage 26, and suitably secured thereto is a tail rod 27, which extends through and below the foot valve E. The foot valve proper consists of a casting 28, which is cup shaped or cylindrical in formation. The central portion or the lower side thereof is extended to form a hexagon nut 29, which serves as a guide for the tail rod, and the upper central portion is extended, as at 30, to receive a stuffing gland 31, which may be unscrewed by holding onto the nut 30. The exterior of the stuffing gland is machined to form a guide for the foot valve proper, indicated at 32, and the upper surface of the casting is machined to form a seat for the valve. It will also be noted that the stuffing gland nut is provided with a collar which limits the lift of the valve 32. The exterior surface is grooved to receive a sealing ring 33, and the lower exterior portion is tapered, as at 34, to form a seat and joint with relation to the foot valve cage indicated at 35. This cage is threaded to permit it to be screwed on to the lower end

of the cylinder and it is otherwise provided with an interior machined tapered seat to receive the main casting of the foot valve.

The operation of the pump for one complete reciprocation will be as follows:

When the plunger 3 starts on the downward stroke, the upper discharge or check valve 8 will close and will be held in closed position by the pressure or column of water maintained in the discharge casing C. The water in the well will enter the ports 20 and the annular passage 19, and by reason of the partial vacuum produced by the plunger, valve 7 will open and permit the water to pass downwardly through the by-pass passages 22 into the upper end of the pump barrel or cylinder. The chamber formed in the cylinder below the plunger has already been filled and will during the downward stroke of the plunger or pressure exerted thereby, pass upwardly through the hollow plunger rod and lift the upper check valve 23 from its seat. The water will thus freely discharge between the arms 24 and enter the discharge casing by which it is conveyed to the surface of the well. Foot valve 32 will of course remain in closed position during this stroke as a downward pressure will be exerted thereon. Reversal of the plunger will produce a sufficient vacuum or suction in the lower end of the cylinder to lift the foot valve 32 and permit the water in the well to freely enter. The upper check valve 23 will simultaneously seat, due to the partial vacuum produced, and the pressure exerted by the water column in the discharge casing. The water admitted to the upper end of the pump cylinder will, during the reversal of the plunger, pass in an upward direction through the by-pass passages or ports 22, and will at the same time exert a pressure which will close the lower check valve 7, and conversely lift or open the upper check valve 8. Water under pressure will thus discharge into the casing C, by which it will be conveyed to the surface.

Many important advantages are obtained by the structure so far described: First, it will be readily admitted that practically all deep well pumps are provided with congested port areas or water passages which are usually confined to the inside diameter of the pump cylinder. In the present structure by leading the water from the valve pockets to the outside water passages 22, a practically unlimited area is obtained, which eliminates friction, high velocities, etc., and renders the pump practical. Second, in ordinary pumps it is common practice when making joints to employ a long tapered fit to take in two or more joints or else to make two straight fits of different diameter, figuring the joints to be metal to metal, and forced into place under pres-

sure. Neither method has proven to be satisfactory. In the first place sand or grit has a tendency to enter between the surface of the joints and thus prevents proper seating of the tapered connections. This causes leakage and erosion of the metal between the joints, which in time destroys the fit. Again, if long tapered joints are properly fitted, they usually become so seated of the tapered connections. This causes leakage and erosion of the metal between the joints, which in time destroys the fit. Again, if long tapered joints are properly fitted, they usually become so 5 locked under pressure that it is almost impossible to dislodge them without breaking one connection or another. If two straight fits are employed, it is obvious that they are expensive to produce and are easily 10 scratched or bumped while being installed. After a pump has been overhauled two or three times, such joints begin to leak and they are therefore subject to erosion and wear. In the present instance only two 15 tapered joints are employed, as indicated at 13 and 34. Both joints are fairly short and the members carried thereby are seated independent of each other; further where other joints are required, rubber sealing 20 rings, such as shown at 16, 18 and 33 are employed. These rings are self-expanding and self-seating and they are not materially affected by sand or grit. These rings however 25 form the subject matter of a copending application and will not be further referred to. Third, gravity actuated valves are employed throughout, thus avoiding breakage of springs, etc., which is always a source of considerable trouble. Ample 30 seating surfaces and guides are employed in each instance, thus insuring proper seating and long life of the several parts. Fourth, perfect alignment is maintained between the pump rod and the plunger rod and 35 perfect alignment between the cylinder and the plunger rod is maintained, first by the guides indicated at 24; secondly, by passing the plunger rod through the bearings formed by the valve seat members 11 and 40 12; and third, by the end guide obtained by the use of the tail rod 27. Fifth, all working parts including the foot valve can be readily removed from time to time for inspection, adjustment or repair by an upward pull on the pump rods. The plunger 45 proper will during such upward pull engage the packing gland nut 12^b on the lower end of the valve seat member 12, and by bumping action it is possible to readily unseat or break the tapered joint, 13. A further upward pull will cause the nut on the lower end of the tail rod to engage the hexagon extension 29, and a further bumping action will here cause the tapered joint 50 indicated at 34 to be broken and the entire mechanism may thus be raised to the surface as all moving, reciprocating or working parts have a diameter slightly less than the pump head and cylinder proper, 55 thus permitting them to be readily removed 60

and replaced as occasion may demand, without resorting to the necessity of pulling out the discharge casing C and the pump cylinder proper.

By referring to Fig. 1, it will be seen that 70 the tail rod 27 is surrounded by a bumper spring 40; further that this bumper spring is secured to the upper end or the nut of the packing gland 31. This spring is of great importance as will hereinafter appear. Consider assembling of the parts for removal, and it will be noted that the spring employed is of great importance inasmuch as the two tapered fits indicated at 13 and 34 are considerably interspaced and cannot 75 be seated at the same time through metal to metal contact. This is due to the fact that when the pump is overhauled and not screwed up to exactly the same place, the distance between the tapered fits would be 80 changed and the lower foot valve seat would not be pushed into position as the distance was elongated, and on the other hand if the distance between the two tapers were shortened, the foot valve would seat first 85 and the upper taper would therefore not reach proper position. The spring employed renders this distance flexible and insures proper seating of two tapers at all 90 times irrespective of any change in distance between the two tapered fits. By again referring to Fig. 1, it will be noted that all the edges of the ports 20 and 22, where entering or leaving the main bore 95 of the head member D, are bevelled so as not to interfere with the cup leathers on the plunger 3, or the rubber sealing rings 16, 18 and 33, or any parts of the pump 100 when being installed.

While certain features of the present invention are more or less specifically illustrated, I wish it understood that various changes in form and proportion may be resorted to within the scope of the appended claims, similarly that the materials and 105 finish of the several parts employed may be such as the experience and judgment of the manufacturer may dictate or various uses may demand.

Having thus described my invention, what 110 I claim and desire to secure by Letters Patent is:—

1. In a pump of the character described, the combination with a pump cylinder and the discharge casing, of a hollow head member connecting the cylinder and casing, upper and lower connected valve seat members within the head member and carried thereby, a plunger rod extending through and guided by said valve seat members, a valve on the upper end of each of said valve seat members, by-passes formed in the head and offset with relation to the bore of the head and connecting the upper and lower valves with the upper end of the cylinder, 115 120 125 130

- 4
- said head member having ports formed therein between the by-passes and establishing direct communication between the lower valve and the exterior of the head, whereby
- 5 on the downward stroke of the plunger the upper valve is maintained closed and the water from the well passes through the said ports and upwardly through the lower valve directly to said by-passes so as to lead
- 10 the water around the lower valve seat member and downwardly outside the interior of the head member and directly into the upper end of the cylinder.
2. In a pump of the character described
- 15 the combination with the pump cylinder and the discharge casing, of a head member connecting the cylinder and casing, upper and lower connected valve seat members within the head member and carried thereby, a plunger rod extending through and guided by said members, a valve seat and valve on the upper end of each member, a plurality of interspaced extensions on the head having passages formed therein establishing communication between both valves and the upper end of the cylinder, and ports formed in the head establishing communication between the exterior of the head and the lower valve only.
- 25 3. In a pump of the character described
- 30 the combination with the pump cylinder and the discharge casing, of a head member connecting the cylinder and casing, a tapered annular seat formed in the upper end of the head member, an upper valve seat member adapted to be received and supported thereby, a lower valve seat member secured to the upper member, a valve seat and valve on each member, an annular shoulder on the
- 35 lower member below the valve seat, a sealing ring carried thereby, an annular flange on the lower end of the lower valve seat member, a sealing ring carried by said lower annular flange, an annular passage formed between said flanges exterior of the lower valve seat member, ports formed in the head establishing communication between the exterior surface of the head and said annular passage, and a plurality of by-pass passages
- 40 formed in the head establishing communication between the lower side of the upper valve and the upper side of the lower valve and the upper end of the cylinder chamber.
- 45 4. In a pump of the character described,
- 50 the combination with a pump cylinder and the discharge casing, a plunger rod entering the cylinder, a plunger on the rod, a hollow head member connecting the cylinder and the casing and provided with a plurality of
- 55 outwardly directed by-passes offset with relation to the bore of the head, a pair of check valves within said head member operating with the upper end of the cylinder, the head member having ports leading into the interior of the head member,

whereby on the downward stroke of the plunger the water from the well is led from the well into the head member and caused to pass around the lower check valve and through said by-passes and directly into the end of the cylinder, a foot valve in the lower end of the cylinder, a tail rod carried by the plunger projecting through and guided by the foot valve, and means on said rod engageable with the foot valve to remove the

75 same in unison with the plunger.

5. In a pump of the character described, the combination with a pump cylinder and the discharge casing, a hollow head member connecting the cylinder and the casing and including an annular chamber provided with ports to lead water from the well into the chamber, spaced by-passes formed in the head member and offset with relation to the bore of the head and having communication with said annular chamber, a plunger reciprocally mounted in the cylinder, a hollow plunger rod connected thereto, a check valve in the upper end of said rod cooperating with the lower end of the cylinder, a foot valve in the lower end of the cylinder cooperating with the aforesaid check valve, a tail rod carried by the plunger and projecting through and guided by the foot valve, and a pair of check valves carried in the head member, one above and the other below said annular chamber and operable so that on the down stroke of the plunger the upper valve is closed by the column of water in the discharge casing and the water from the well is caused to open the lower check valve in the head member and caused to flow around the lower check valve seat and downwardly by way of said by-passes into the upper end of the cylinder.

6. In a pump of the character described, the combination of a pump cylinder and a discharge casing, a hollow head member connecting the cylinder and casing and having means to permit inflow of water thereinto from the well, a plunger mounted for reciprocation in the cylinder, a pair of valves in said head member, and means offset with relation to the bore of the head whereby on the down stroke of the plunger to convey the water from the interior of the head member around and downwardly past the lowermost valve through said offset means directly to the upper end of the cylinder.

7. In a pump of the character described, the combination with the cylinder and the plunger reciprocally mounted therein, of a sleeve secured on the lower end of the cylinder, an annular tapered seat in said sleeve, a foot valve adapted to be received and supported thereby, a tail rod secured on the plunger projecting through and guided by the foot valve, a head member on the lower end of the rod engageable with

120

125

130

the lower side of the foot valve to unseat and lift it with relation to the annular seat when the plunger is removed from the cylinder, a spring surrounding the rod intermediate the 5 foot valve and the plunger, and means on the plunger engageable with said spring to force the foot valve against the tapered seat.

8. In a pump of the character described, the combination of a pump cylinder and a 10 discharge casing, a hollow head member, connecting the cylinder and casing and having means to permit inflow of water from the well, a plunger mounted for reciprocation in the cylinder, a pair of check valves in said 15 head member, both disposed above the point of inflow of water from the well into the head member, and means whereby on the down stroke of the plunger to convey the water in the head member to the outside of 20 the latter and downwardly past the lowermost of said valves directly to the upper end of the cylinder.

9. In a pump of the character described the combination with the cylinder and the 25 discharge casing, of a head member connecting the same, a plurality of interspaced enlargements on the head, each having a water passage formed therein, a plunger rod extending through the head, a guide therefor 30 carried by the head, a pair of annular ring shaped check valves carried by the guide, the upper side of one valve and the lower side of the other valve being in communication 35 with the upper ends of the water passages and the lower end of the water passages being in communication with the upper end of the cylinder, and means for admitting water from the exterior of the head to the lower side of the lower valve.

10. In a pump of the character described the combination with the pump cylinder and the discharge casing, of a head member connecting the cylinder and casing, a pair of 40 valve seat members, a check valve supported by each, a tapered seat in the head member supporting said valve seat members, a plunger rod extending through and guided by the seat members, a plunger thereon, a foot valve unit in the lower end of the cylinder, 45 a tapered seat for the reception of said foot valve unit, means actuated by the plunger for unseating the foot valve unit, and the valve seat members in substantial unison, resilient means actuated by the plunger for 50 seating the foot valve unit, and other means for simultaneously seating the valve seat members.

11. In a pump of the character described, the combination with the cylinder and the 55 plunger reciprocally mounted therein, of a foot valve unit disposed in the lower end of the cylinder, a tapered seat formed in the lower end of the cylinder for the reception of the foot valve unit, a tail rod carried by the 60 plunger projecting through and guided by

the foot valve unit, a head member on the lower end of the rod engageable with the lower side of the foot valve unit to permit unseating and removal of the foot valve unit in unison with the plunger, and resilient 70 means interposed between the plunger and the foot valve unit and engageable by the plunger to seat the foot valve unit.

12. In a pump of the character described, the combination with the cylinder and the 75 plunger reciprocally mounted therein, of a foot valve unit disposed in the lower end of the cylinder, a tapered seat formed in the lower end of the cylinder for the reception of the foot valve unit, a tail rod carried by 80 the plunger projecting through and guided by the foot valve unit, a head member on the lower end of the rod engageable with the lower side of the foot valve unit to permit unseating and removal of the foot valve unit 85 in unison with the plunger, resilient means interposed between the plunger and the foot valve unit and engageable by the plunger to seat the foot valve unit, and a sealing 90 ring carried by the foot valve unit and engageable with the inner surface of the cylinder.

13. In a pump of the character described, the combination with a pump cylinder and the discharge casing, of a head member connecting the cylinder and casing, upper and lower valves confined within the head member, the head member having a plurality of spaced passages to establish communication 95 between both valves and the upper end of the cylinder and also having a plurality of ports to establish communication between the exterior of the head and the lower valve.

14. In a pump of the character described, the combination with the pump cylinder 100 and the discharge casing, of a head member connecting the cylinder and casing, upper and lower valves arranged within the head member, the head member having a plurality of spaced vertical passages establishing 105 communication between both valves and the upper end of the cylinder, and also having a plurality of ports formed therein between the passages to establish communication between the exterior of the head and the lower 110 valve.

15. In a pump of the character described, the combination of a pump cylinder, a discharge casing, a hollow head member connecting the cylinder and casing and having 115 an annular chamber confined therein, said chamber having means to establish communication with the well, a plunger mounted for reciprocation in the cylinder, a pair of valves in the head member, both disposed above the point of inflow of water from the well into said annular chamber, and means whereby on the down stroke of the plunger, water from said annular chamber confined 120 within the head member is conveyed up 125

wardly through and around the lower valve and downwardly outside of the annular chamber directly to the upper end of the cylinder. and by-passes having communication with said annular chamber whereby on the down stroke of the plunger, the water is led into the chamber from the well through the aforesaid ports, and is directed upwardly through the lowermost valve and downwardly on the outside of the circumference of the annular chamber directly to the upper end of the cylinder.

- 5 16. In a pump of the character described, the combination of a pump cylinder, a discharge casing, a hollow head member connecting the cylinder and casing and having an annular chamber confined therein, the 40
10 head member having ports therein to permit water from the well to flow into the annular chamber, a plunger mounted for reciprocation in the cylinder, a pair of valves in the head member, both disposed above 45
15 said ports, and a by-pass offset with relation to the head member and having communication with said annular chamber within the head member whereby on the down stroke of the plunger, the upper valve is 50
20 maintained closed and the water from the well passes through said ports into said annular chamber and upwardly from the latter through the lower valve and downwardly through said by-pass directly to the upper 55
25 end of the cylinder.

17. In a pump of the character described, the combination of a pump cylinder, a discharge casing, a hollow head member connecting the cylinder and casing and having an annular chamber confined within the head member, the chamber having ports to permit water from the well to flow into the annular chamber, a hollow plunger mounted for reciprocation in the cylinder, a pair of superimposed spaced valves in the head member, both disposed above said ports, by-passes having communication with said annular chamber whereby on the down stroke of the plunger, the water led into the chamber from the well through the aforesaid ports, is directed upwardly through the lowermost valve and downwardly on the outside of the circumference of the annular chamber directly to the upper end of the cylinder, the hollow plunger having a hollow plunger 60
30 rod extending therefrom and a valved outlet disposed in the line of the hollow plunger above the aforesaid valves and operable to permit discharge of water into the discharge casing. 65
